UNITED STATES PATENT OFFICE.

HENRY E. MORTON, OF MUSKEGON, MICHIGAN.

TRAVELING-HEAD SHAPER.

1,167,649.

Specification of Letters Patent.

Patented Jan. 11, 1916.

Application filed July 6, 1914. Serial No. 849,238.

To all whom it may concern:

Be it known that I, HENRY E. MORTON, a citizen of the United States of America, residing at Muskegon, in the county of Muskegon and State of Michigan, have invented certain new and useful Improvements in Traveling-Head Shapers, of which the following is a specification, reference being had therein to the accompanying drawings.

10 This invention relates to improvements in traveling head shapers or planers and more particularly to that class of shapers which are designed for heavy work and embody reciprocable tool carrying rams.

15 The object of the invention is to make such machines applicable to other kinds of work without complicating their construction or affecting their operation as shapers, and to provide an attachment adapted to be 20 readily fixed to the ram to be carried thereby and driven independently of the movements of the ram or traveling head.

With these and other ends in view the invention consists in providing the ram of a 25 shaper with an arbor for transmitting motion to the extended end thereof and mounting upon said end an attachment which may be quickly applied thereto or detached therefrom to be driven by said arbor, said attachment embodying certain new and useful 30 features in its construction, all as herein-after more fully described and illustrated in the accompanying drawing, in which—

Figure 1 is an end elevation of a traveling head shaper showing the same as provided with a reciprocable ram and rotary cutter or planer applied thereto, embodying the invention; Fig. 2 is an enlarged sectional detail of the ram and cutter attachment; Fig. 3 is a transverse section of the ram showing the attachment in elevation, and Fig. 4 is a sectional detail showing a modified construction of cutter head.

In Fig. 1 of the drawings, the invention 45 is shown as applied to a traveling head, draw-cut planer or shaper of the type shown in Patent No. 682,218, of September 10, 1901, issued to M. and H. E. Morton, especially adapted for heavy work such as cylinders and other large parts of locomotive and other engines and machinery; but it 50 will be understood that it may be applied as

well to any planer or shaper having a tool carrying ram, and I do not, therefore, limit myself to the particular construction of 55 shaper or planer shown. The machine shown in Fig. 1, is of the type known as a draw-cut shaper and comprises a suitable base or bed A upon which is mounted a traveling head B carrying a vertically movable apron C provided with a bearing for a longitudinally reciprocable ram 1. The mechanism for moving the head B, raising and lowering the apron C and reciprocating the ram, is not shown in detail, as it forms 60 65 no part of this invention.

As clearly shown in Figs. 2 and 3, the ram 1 is preferably rectangular in cross section and is formed hollow or with a longitudinal bore to receive a tubular shaft or arbor 2 70 which extends therethrough and is provided at the free or forward end of the ram with a tapered seat 3 for the tapered shank or hub 4 of a pinion 5, said hub being provided with a key 6 to engage a key-way in the 75 seat 3. The inner end of the hub is also formed with an axial screwthreaded socket to receive the screwthreaded end of a locking rod 7 which extends longitudinally through the arbor and is provided with a 80 collar 8 near its rear end to engage a suitable sleeve 9 having screwthreaded engagement with the screwthreaded end of the bore of the arbor. A second collar 10 fixed on the rod 7 engages the outer end of the 85 adjusting sleeve 9 and the projecting outer end of the rod is formed to receive a wrench by means of which it may be turned to engage its screwthreaded opposite end with the hub of the gear 5. 90

The gear 5 is detachably secured to the arbor 2 to turn therewith and may be readily disengaged therefrom by means of the rod 7, said rod being held against longitudinal movement and adjusted longitudinally 95 in the arbor by means of the adjusting sleeve 9 which turns freely upon the rod between the collars 8 and 10. After the hub 4 of the gear has been engaged with its tapered seat in the end of the arbor, the 100 rod is run through the arbor and attached to the hub by turning the rod to engage its screwthreaded end with the screwthreaded socket of the hub, the adjusting sleeve 9

being at the same time screwed into the rear end of the arbor. After the rod has been engaged with the hub of the gear, the sleeve is turned upon the rod in a direction to 5 move it outwardly and thus exert a pull on the rod which will draw the hub into its seat and firmly lock the gear upon the end of the arbor. When it is desired to detach the gear, the sleeve 9 is turned to move 10 the rod in an opposite direction and force the hub out of engagement with its seat.

A suitable gear carriage or casing 11 is secured to the rear end of the ram 1, and within this casing is a large gear 12 keyed 15 to the projecting end of the arbor 2. Motion is transmitted to this gear to turn the arbor, by means of a train of gears 13 which is driven by a pinion 14 in the casing mounted upon a driving shaft 15 adapted to slide 20 longitudinally through bearings in the casing and having a longitudinal key or spline 16 for driving the pinion 14. Power is applied to turn the drive shaft in any suitable manner, not shown, and thus the arbor 2 is 25 rotated by the splined drive shaft which permits of a longitudinal reciprocation of the ram.

The rotary cutter or planer attachment for the ram comprises a suitable head or 30 saddle 17 formed to fit over the ram 1 near its forward end and is held firmly in place thereon by means of clamping bars 18 and bolts 19. The saddle is bored longitudinally 35 through its enlarged portion at the upper side of the ram to form a suitable bearing for the stub shaft 20 of the rotary cutter which consists of a disk 21 formed integral with the forward end of the stub shaft and is provided with a series of notches in its 40 periphery to receive cutting tools 22 held in place by means of clamping bars 23 and bolts 24. The forward face of the disk 21 is a plane surface but the rear side of the disk is cut away to provide an over-hanging 45 peripheral flange 25 which is formed with internal gear teeth 26 adapted to mesh with the teeth of the pinion 5. A circular flange 27 on the forward end of the saddle 17 fits into the recess in the back of the disk 21 and 50 this flange is provided with a suitable facing 28 between it and the adjacent surface of the disk. The flange 27 thus forms a backing for the disk so that when heavy pressure and strain is applied to the disk at one edge 55 thereof in operation, the disk will be firmly held against tilting or springing and binding of its shaft 20 in its bearing will be avoided.

To prevent the projecting end of the ram 60 which carries the rotary cutter from springing or getting out of alinement, a suitable bracket 29 is bolted to an adjacent part of the supporting frame work of the machine, such as a face plate (not shown) carried

by the apron C, and this bracket extends 65 outwardly and over the saddle 17 where it is formed with a suitable groove to receive an upwardly projecting rib 30 on the saddle and is made fast thereto by bolts 31 passing through slots 32 in the head of the bracket 70 and engaging screwthreaded openings in the saddle. The outer end of the arm is thus rigidly supported by the bracket which permits of the adjustment of the rotary cutter to the work by loosening the bolts 31 so that 75 the arm may be projected slightly to carry the cutter toward the work. As the bracket and arm are carried by the traveling head B of the shaper, the cutter may be moved past the work with a continuous feed by 80 means of the mechanism (not shown) which is provided for reciprocating the head along the bed A of the machine. The cutter may also be raised and lowered with a continuous feeding movement by the mechanism 85 (not shown) for actuating the apron C with a feeding movement.

As shown in Fig. 1, a suitable work supporting table 33 is provided for supporting work 34 in position to be operated upon by 90 the rotary cutter, and in Fig. 4 means is shown for supporting one end of a boring bar and driving the same so that such a tool may also be used upon this class of machines to do certain kinds of work without the necessity for resetting the work after the shaping, planing or other operations have been completed, or where the work is so large that it cannot be readily done on other machines. The boring bar holder comprises a socket member 35 which is bolted or otherwise secured to the front face of the disk 21 and is formed with a tapered bore to receive the tapered end of a suitable boring bar 36. The bar is held in the socket by 100 means of a suitable wedge key 37 engaging slots in the sides of the socket and an opening in the bar.

The cutting operation of the rotary cutter is performed at the advance side of 110 the cutter in the direction of its feeding movement and to prevent the engagement of the cutters with the work at the rear edge of the cutter, it is necessary to tilt the saddle slightly upon the ram so that 115 the axis of the stub shaft 20 will extend at a slight angle to the axis of the arbor 2. This adjustment of the saddle is secured by means of set screws 38 extending through one leg of the saddle at one side of the arm 120 into engagement with a gib 39 resting against the side of the arm, suitable shims (not shown) being placed between the other leg of the saddle and the opposite side of the ram. Set screws 40 are also provided 125 on the bracket 29 to engage a gib 41 lying against the side of the rib 30 on the saddle for the same purpose.

By providing a hollow ram with an arbor extending therethrough, suitable cutting tools of various forms may be applied to the end of the ram and driven by means of the arbor, thus adapting the shaper of the class shown to various forms of work other than draw-cut shaping. The particular construction and arrangement of rotary planing attachment gives a very powerful rotary planer which may be quickly adjusted and attached and is adapted for use in planing various forms of heavy machinery, the work 34 illustrated in Fig. 1 being a number of eccentric straps for locomotives which are being faced off by means of the rotary planer as applied to the ram of the draw-cut shaper.

Obviously changes may be made in the details of construction without departing from the spirit of my invention, and I do not therefore limit myself to the particular construction shown.

What I claim is:

1. The combination with the head and driving mechanism of a shaper, of a tool carrying ram actuated by said mechanism, said ram having an axial bore, an arbor mounted in said bore, means actuated by said driving mechanism for rotating said arbor, and a cutting tool mounted on said ram to turn upon an axis at one side of a parallel with the axis of said arbor and driven by said arbor.

2. The combination with the head and driving mechanism of a shaper, of a tool carrying ram actuated by said mechanism, said ram having an axial bore, a tubular arbor in said bore, an actuating member detachably connected to one end of the arbor to turn therewith, a rotatable cutting tool actuated by said member, a bearing member detachably mounted on said ram and having a bearing for the tool, said tool and arbor being adapted to rotate upon parallel axes, and means extending through said arbor for detachably holding said actuating member engaged with the arbor.

3. The combination with the head and driving mechanism of a shaper and a tool carrying ram, of a member detachably secured to the free end of the ram and provided with a bearing for a tool, a rotatable cutting tool mounted in the bearing on said member, and means carried by and movable with the ram for transmitting motion from said driving mechanism to rotate the tool independently of the movement of the ram.

4. The combination with the ram of a shaper or planer, of a saddle formed with a seat to engage the ram, means for detachably securing the saddle in place upon the ram, a rotary tool mounted on the saddle, and means carried by the ram for actuating the tool.

5. The combination of a ram for a shaper

or planer having an axial bore, an arbor 65 in said bore, a saddle having a seat to engage the side of the ram, means for detachably holding the saddle seated upon the ram, a rotary tool mounted on the saddle, and means on the arbor for actuating the 70 rotary tool.

6. In a shaper or planer having a traversing member, a reciprocable tool carrying ram, and means for actuating said member and ram, of a rotary cutting tool detachably 75 secured to the free end of the ram, means for rotating the tool independently of the movements of the member and ram, and a supporting member detachably connected to the ram near its end upon which the rotary 80 cutter is supported and secured to said traversing member to brace the tool carrying end of the ram.

7. The combination with the ram of a shaper or planer, of a carrying member 85 detachably secured to the end of the ram and formed with a bearing extending longitudinally of the ram, a shaft in said bearing, a circular head on said shaft having peripheral cutters, and means for rotating said 90 head.

8. The combination with the ram of a shaper or planer, of a carrying member detachably secured to the end of said ram, a disk mounted on said member to rotate in 95 a plane at substantially right angles to the longitudinal axis of the ram, cutters on the disk, and means supported by the ram for rotating the disk.

9. The combination of a hollow ram for 100 shapers or planers, an arbor in said ram, a saddle on the free end of the ram, a circular cutter member mounted on the saddle to rotate in a plane substantially at right angles to the longitudinal axis of the ram, said 105 cutter member being provided with an internal gear, and a pinion on the arbor in mesh with the gear to rotate the cutter member.

10. The combination of a hollow ram for 110 shapers or planers, an arbor in said ram, a saddle detachably mounted on said ram and having a bearing extending longitudinally of the ram, a shaft in said bearing, a disk on the end of the shaft, a series of 115 cutters on the periphery of the disk, and means on the arbor for rotating the disk.

11. The combination with the ram of a shaper or planer, of a saddle detachably secured upon the ram and having a bearing, 120 a shaft in said bearing, a disk on the end of the shaft, a circular flange on the saddle opposing the rear face of the disk, a series of cutters secured to the periphery of the disk, and means for rotating the disk.

12. In a shaper or planer, the combination with the traversing head, vertically movable aprons and driving mechanism

therefor, of a hollow ram mounted on the apron and reciprocated by said driving mechanism, an arbor in said ram, a train of gearing carried by the ram for actuating the arbor, a splined shaft for transmitting motion from the driving mechanism to said gearing and permitting a reciprocation of the ram, and a rotary tool carried by the

outer end of the ram and actuated by said arbor. 10

In testimony whereof I affix my signature in presence of two witnesses.

HENRY E. MORTON.
